(57) **CLAIM**

The ornamental design for an electrical receptacle bracket for an electrical distribution harness, as shown and described.

DESCRIPTION

FIG. 1 is a perspective view of an electrical receptacle bracket for an electrical distribution harness showing my new design, in use condition;

FIG. 2 is a perspective view thereof;

FIG. 3 is a front view thereof;

FIG. 4 is a rear view thereof;

FIG. 5 is an end view thereof;

FIG. 6 is an opposite end view thereof;

FIG. 7 is a top view thereof; and,

FIG. 8 is a bottom view thereof.

The broken line portion of the figure drawings is included for the purpose of illustrating environment and forms no part of the claimed design.
